US0D1084846S

(12) **United States Design Patent** (10) **Patent No.:** **US D1,084,846 S**
(45) **Date of Patent:** **** Jul. 22, 2025**

(54) **CONTAINER**

(71) Applicant: **STASHER, INC.**, Emeryville, CA (US)

CN 302806581 S 4/2014
CN 305602228 S 2/2020

(72) Inventor: **Angelo Carpinelli**, Emeryville, CA (US)

(Continued)

(73) Assignee: **Stasher, Inc.**, Emeryville, CA (US)

(**) Term: **15 Years**

(21) Appl. No.: **29/806,416**

(22) Filed: **Sep. 2, 2021**

(Continued)

FIG. 1 is a top, front, and right side isometric view of a container;

FIG. 2 is a bottom, rear, and left side isometric view of the container of FIG. 1;

FIG. 3 is a front elevational view of the container of FIG. 1; FIG. 4 is a rear elevational view of the container of FIG. 1; FIG. 5 is a left side elevational view of the container of FIG. 1;

FIG. 6 is a right side elevational view of the container of FIG. 1;

FIG. 7 is a top plan view of the container of FIG. 1; and, FIG. 8 is a bottom plan view of the container of FIG. 1. The dash-dash-dash lines are included for the purpose of illustrating portions of the container that form no part of the claimed design.

1 Claim, 8 Drawing Sheets
